UNITED STATES PATENT OFFICE.

LESSIE WHIPPLE AND ZACK ONEAL, OF SHREVEPORT, LOUISIANA.

SAFETY SCALEPROOF AUTOMATIC GAGE-COCK.

1,388,624.

Specification of Letters Patent. Patented Aug. 23, 1921.

Application filed November 16, 1920. Serial No. 424,507.

To all whom it may concern:

Be it known that we, LESSIE WHIPPLE and ZACK ONEAL, citizens of the United States, and residents of Shreveport, in the parish of Caddo and State of Louisiana, have invented certain new and useful Improvements in Safety Scaleproof Automatic Gage-Cocks, of which the following is a specification.

10 Our invention relates to improvements in gage cocks and has special reference to that class of gage cocks using multiple valves and which are adapted to be used in connection with locomotive boilers.

15 An object of the invention is to provide an improved separable gage cock of such construction as to admit of the main or outlet valve and stem being removed for regrinding and other repairs without removing the 20 entire assembly from the boiler, and at the same time automatically closing the steam or water outlet from the boiler, and thus obviating the necessity of withdrawing the steam from the boiler.

25 Another object is to prevent the gage cock from becoming inoperative through deposit or accumulation of lime or scale on the valve seat.

With these and other objects in view as 30 will appear as the description proceeds, the invention consists in certain novel features of construction, arrangement and combination of parts as will be hereinafter fully described and pointed out in the claims, reference being had to the accompanying drawing in which—

Figure 1 is a side elevation showing the gage cock applied to a boiler.

Fig. 2 is a vertical longitudinal section 40 of the same.

Fig. 3 is a vertical transverse section taken on line 3—3 of Fig. 2.

Fig. 4 is a similar view taken on line 4—4 of Fig. 2.

45 Fig. 5 is a vertical transverse section taken on line 5—5 of Fig. 2.

Fig. 6 is a perspective view of the automatically operating valve removed from the body portion.

50 Fig. 7 is a perspective view of the automatic valve cage, or cover, shown separated from the body portion.

Fig. 8 is a perspective view of the main valve and stem removed from the body portion.

55

Similar reference characters refer to similar parts throughout the several views.

In a practical embodiment of our invention we employ a gage cock body portion 10 which has a globular or spherical outlet 60 chamber 11 from which leads an outlet pipe 12. The outer end beyond the spherical chamber constitutes a neck 13 which is externally and internally threaded and into the threaded bore 14 of the neck is introduced the main valve 15 the stem of which is threaded as at 16 to mate with its internal thread; this stem is also reduced and projects beyond the body portion as a turning staff 17 to the end of which is rigidly attached a hand wheel 18 as usual in this type of device.

The main valve 15 is of the cone frustum type and has projecting from its inner end an axial pin 19 the purpose of which will 75 later appear. After the main valve has been introduced into the neck until the threaded portion is within the outer end of the threaded neck a packing ring or gasket 20 is slipped on the handle stem against the 80 annular shoulder formed by the junction of the reduced stem and the threaded portion; a bonnet or gland cup 21 is then screwed on the externally threaded neck and compresses the packing gasket and holds tightly in place 85 and renders the gage cock leak proof at this point.

The rear wall of the spherical chamber has a cone frustum valve seat 22 with which the cone frustum valve mates and the valve is 90 tightly seated in the valve seat by screwing in the valve stem by means of the hand wheel. The bore 23 of the gage cock then extends axially rearwardly or inwardly 95 through the body portion and then flares or expands into another cone frustum valve seat 24 at the extreme inner end of body or that portion that is to lie within the boiler.

The body is secured in the head of the boiler 25 by a tapered threaded portion 100 26 screwed into a similarly tapered and threaded opening in the head of the boiler.

The inner end of the body beyond the aforesaid tapering threaded portion is re-

duced as at 27 and externally threaded and upon this threaded end is screwed a cage 28 the end wall of which has an axial opening 29 and a circular series of similar 5 openings 30 surrounding the central opening, said central opening receiving and guiding the end of valve stem 31 which carries at its opposite end the cone frustum valve 32 adapted to seat in valve seat 24; surrounding 10 the stem 31 is a coiled expansion spring 33 which bears at one end against the valve 32 and at its opposite end against the end wall of the cage, the tendency of this spring being to aid the pressure within the boiler to force 15 valve 32, to its seat.

Projecting from the smaller end of valve 32 is a plunger 34, which is substantially triangular in cross section and extends into the central bore of the body and through the 20 same to a point adjacent the main valve seat, and its free end is provided with a cylindrical depression or socket 35 designed to receive the free end of pin 19 which extends beyond the main or outlet valve.

25 When in use the tapering threaded portion is screwed in the boiler head, the auxiliary or cage valve being held to its seat by coiled spring 33. The gage cock now being secured to the boiler, by screwing in the 30 valve stem 16 the pin 19 will enter the recess or socket 35 in the end of plunger 34 and forcing the same will unseat the valve 32 against the force of the spring 33 and the pressure of water and steam within the 35 boiler and permit the passage of water to the outlet 12. When the main valve stem is screwed entirely into the body the main valve 15 becomes seated and the auxiliary valve is full open.

40 If it is now desired to regrind the valve seat or the main valve, or to make any other repairs to the main valve chamber, the bonnet 21 is unscrewed from the neck of the body and the main valve stem unscrewed 45 from the body of the cock, whereupon the auxiliary or cage valve will be automatically seated, the coiled spring aiding the pressure in the boiler to accomplish this result, and thus preventing the danger of scalding while 50 the repairs are made to main valve end of the device.

The plunger 34 being substantially triangular and having a loose fit in the bore, spaces are left surrounding and as it may 55 turn on its axis either by the force of the water or by a turning movement of the

main valve stem through the pin 19, accumulation of scale will be prevented.

We claim:—

1. A gage cock comprising a body portion 60 having a spherical main valve chamber, and a transverse outlet therefrom and an internally and externally threaded neck beyond said chamber, said chamber having an axial cone frustum valve seat in its wall opposite 65 the neck, a valve stem threaded into said neck, a cone frustum valve on said stem and a pin projecting from said stem beyond said valve, a packed bonnet surrounding said stem and screwed on said neck, the body 70 portion having a tapering threaded portion fitted into the boiler head and a reduced threaded end beyond said tapering threaded portion, a cage screwed on said reduced end and having a central guide opening through 75 its end wall and a circular series of openings surrounding said guide opening, an auxiliary cone frustum safety valve, within said cage, and a stem projecting from the larger end of said valve projecting through 80 said guide opening, a coiled spring surrounding said stem between the valves and the end wall of the cage, said valve adapted to be seated on a cone frustum valve seat at the end of the bore of the body portion, a 85 substantially triangular plunger projecting into said bore of the body and extending to adjacent the main valve seat, the free end of said plunger having a recess or socket adapted to receive the end of said pin projecting beyond the end of the main valve 90 stem.

2. In a gage cock, a body portion having a spherical main valve chamber adjacent one end and a manually operated, main valve 95 screwed into such end, said body portion adapted to be screwed into a boiler head and having a central bore, a cage screwed onto the other end of the body, said cage having a central opening in its end wall, an 100 auxiliary valve carrying a plunger extending into said bore and loosely mounted in said cage and adapted to automatically control the inner end of the bore of the body, said plunger cooperating with the main valve, a stem projecting through said central opening in the end wall of the cage, said end wall having a series of openings surrounding said central guide opening.

LESSIE WHIPPLE.
ZACK ONEAL.
